Primary Examiner — John Windmuller(74) *Attorney, Agent, or Firm* — Durham Jones & Pinegar, P.C., Intellectual Property Law Group(57) **CLAIM**

The ornamental design for a self-locking tie, as shown and described.

DESCRIPTION

FIG. 1 is a perspective view of my new design for a self-locking tie;

FIG. 2 is a top view of the self-locking tie shown in FIG. 1; FIG. 3 is a bottom view of the self-locking tie shown in FIG. 1;

FIG. 4 is a first side view of the self-locking tie shown in FIG. 1;

FIG. 5 is a second side view of the self-locking tie shown in FIG. 1;

FIG. 6 is a first end view of the self-locking tie shown in FIG. 1; and,

FIG. 7 is a second end view of the self-locking tie shown in FIG. 1.

Broken lines are used in the drawings to illustrate features that form no part of the claimed design.

1 Claim, 2 Drawing Sheets(56)
